Arthur B. Jenkins
ATTORNEY.

UNITED STATES PATENT OFFICE.

OSCAR B. WELKER, OF MIDDLETOWN, CONNECTICUT, ASSIGNOR TO THE WELKER-HOOPS MANUFACTURING COMPANY, OF MIDDLETOWN, CONNECTICUT, A CORPORATION OF CONNECTICUT.

CAP FOR CONTAINERS.

Application filed April 7, 1923. Serial No. 630,468.

To all whom it may concern:

Be it known that I, OSCAR B. WELKER, a citizen of the United States, and a resident of Middletown, in the county of Middlesex and State of Connecticut, have invented new and Improved Caps for Containers, of which the following is a specification.

My invention relates to that class of devices that are commonly used in connection with various types of containers, the contents of which have to be replenished at more or less frequent intervals, and an object of my invention, among others, is to provide a cover for these containers that shall have a maximum efficiency both as to tightness to prevent the contents of said containers or similar devices from splashing or leaking out through said cover, and as to means whereby the mouth of a container may be opened or closed and the cover may also be locked by a very simple and easy operation of a handle. A further object of the invention is to provide a cover that can be easily attached to the opening of a container in common use without the aid of tools to replace the ordinary removable cover supplied therewith, and so constructed that it will not necessitate its removal from the container when it is desired to uncover said opening.

One form of device embodying my invention and in the construction and use of which the objects herein set out, as well as others, may be attained, is illustrated in the accompanying drawings, in which—

Figure 1 is a view in vertical section through a cover embodying my invention, the operating handle being shown in full.

Figure 2 is a similar view of the device taken at right angles to the point of view of Figure 1.

Figure 3 is a plan view of the device showing the cover in the unlocked position.

It is a well known fact, especially in connection with covers which are removably attached to containers such as are used for automobile gasoline tanks, radiators and the like, that require the frequent removal of the cover for the purpose of filling the container, that it is often forgotten to replace the cover, which fact being unnoticed

at the time results in said cover being consequently lost. With my device as hereinafter described this cannot happen.

55

In the accompanying drawings the numeral 7 denotes a ring shaped supporting member having a screw threaded portion 8 which provides a suitable means by which my device can be secured to the threaded flange 9, that is commonly used in connection with containers of the character herein disclosed. The numeral 10 denotes a section of one of these containers.

60

The supporting member 7 has formed thereon ears 11 to which is hinged, by a pin 12, an ear 13 secured to a cover plate 14. This cover plate has a flange 15 which overhangs the edge of the supporting member 7 and also serves to contain within the cover plate a washer 16. An operating handle 17 has an operating stud 18 projecting through the cover plate and on which a baffle plate 19 is mounted. The end of this stud is squared as at 20 and has secured thereto a locking bar 21 supplemented by a washer 22.

70

The locking bar 21 engages locking flanges 23 on the supporting member 7, which flanges are preferably an integral part of said member. These locking flanges have an inclined cam shaped surface at their under sides and they are separated by spaces 24—24 which permit the passing of the locking bar 21 to its proper position when the cover is closed.

75

It can readily be seen that when the cover is closed the ends of the locking bar pass through the spaces 24—24 and that by a simple turn of the operating handle 17 this bar is turned into contact with the cam surfaces of the locking flanges that tend to pull down the cover tightly into engagement with the supporting member 7. The recess in the ear 13 being larger than the pin 12 it will allow the cover plate sufficient play to enable it to properly seat. Studs 25 on the locking flanges are employed as stops to limit the travel of the locking bar.

90

As the locking bar 21, as shown herein, is formed of spring material it will tend to keep the cover tightly closed and still will not bind nor become loose. In connection with covers for containers of the character

100

herein described it is, in the majority of cases, necessary to supply a vent for the interior of the container. This I accomplish with my improved device, by means of a 5 vent opening 26 in the baffle plate 19 and a similar opening 27 in the cover plate 14. By the use of the baffle plate any leakage due to the splashing of the contents is prevented, since this plate will obstruct the 10 passage of the contents through the opening 27 and part of the contents which may happen to splash through the opening 26 will flow back into the container. This baffle plate is so constructed that it also 15 serves as a spacer plate to properly position the locking members. It will be seen that my improved device may be attached to the outlet of a container in the same manner as the ordinary screw cap therefor, and after 20 such attachment will provide a cover that cannot be misplaced.

I claim:

1. A container cap including a supporting member, a closure member hinged to one 25 end of the supporting member, a locking bar rotatably supported within the cover with the opposite ends thereof cooperating with the supporting member for retaining the closure member in closed position and a baffle plate interposed between the closure member and locking bar for retaining the locking bar properly positioned relative to the supporting member.

2. A container cap including a supporting 35 member, a closure member hinged to one end of the supporting member, a locking bar rotatably supported within the cover with the opposite ends thereof cooperating with the supporting member for retaining the closure member in closed position, a baffle plate interposed between the closure member and locking bar for retaining the locking bar properly positioned relative to the supporting member, the supporting means for 40 the locking bar including a stud rotatably mounted in the closure member with the locking bar supported at the lower end of

the stud, and an interlocking connection between the stud and locking bar.

3. A container cap including a supporting member, a closure member hinged to one end of the supporting member, a locking bar rotatably supported within the cover with the opposite ends thereof cooperating with the supporting member for retaining the closure member in closed position, the supporting means for the locking bar including a stud rotatably mounted in the closure member with the locking bar supported at the lower end of the stud, an interlocking connection between the stud and locking bar including the provision of a polygonal portion on the stud, and a similarly shaped opening in the locking bar receiving the polygonal portion and a baffle plate of 55 dished disk formation supported on the stud and engaging the closure member and locking bar for retaining the latter properly positioned on the stud.

4. A container cap including a supporting 70 member, a closure member hinged to one end of the supporting member, a locking bar rotatably supported within the cover with the opposite ends thereof cooperating with the supporting member for retaining the closure member in closed position, the supporting means for the locking bar including a stud rotatably mounted in the closure member with the locking bar supported at the lower end of the stud, an interlocking 75 connection between the stud and locking bar, including the provision of a polygonal portion on the stud, a similarly shaped opening in the locking bar receiving the polygonal portion and a baffle plate of 80 dished disk formation supported on the stud and engaging the closure member and locking bar for retaining the latter properly positioned on the stud, and the adjacent upper portion of the stud being cylindrical 85 in cross-section and supporting the baffle plate.

OSCAR B. WELKER,
